FIG. 6

UNITED STATES PATENT OFFICE.

RICHARD K. LE BLOND AND WILLIAM F. GROENE, OF CINCINNATI, OHIO, ASSIGNEES
TO THE R. K. LE BLOND MACHINE TOOL COMPANY, OF CINCINNATI, OHIO, A COR-
PORATION OF OHIO.

MILLING-MACHINE.

1,152,647.

Specification of Letters Patent. Patented Sept. 7, 1915.

Application filed January 24, 1913. Serial No. 743,918.

To all whom it may concern:

Be it known that we, RICHARD K. LE BLOND and WILLIAM F. GROENE, citizens of the United States of America, and residents of Cincinnati, county of Hamilton, and State of Ohio, have invented certain new and useful Improvements in Milling-Machines, of which the following is a specification.

This invention relates to milling machines and has for an object to produce improved means for controlling the reciprocatory motion of the table, during the operation of the machine. This and other objects, which will be made apparent during the further description of the invention, are attained in a machine embodying the features herein described and illustrated in the drawings accompanying and forming a part of this application.

In the drawings Figure 1 is a fragmental transverse sectional view, along the line 1—1 of Fig. 3, of a machine embodying our invention, and illustrates, in fragmental section, the reciprocable work-supporting table in connection with the feed or actuating shaft of the table and the driving and controlling mechanisms of the feed shaft. Fig. 2 is a side elevation of a reverse plate and 30 gears, employed in connection with the feed drive of the machine. Fig. 3 is a fragmental longitudinal section along the line 3—3 of Fig. 1 and portions are shown partially broken away for convenience of illustration. Fig. 4 is a fragmental sectional view along the line 4—4 of Fig. 3. Fig. 5 is a plan view of the mechanism shown in Figs. 1 and 3 below the table and the feed shaft. Fig. 6 is a fragmental section along the line 6—6 of Fig. 3, and illustrates the means employed for holding the reverse plate of the traverse drive mechanism in the central or inoperative position.

The milling machine herein illustrated as an embodiment of our invention includes a tool support, driving means, and the other equipment usually employed on such machines, but, for the sake of simplifying the illustration and for convenience of description, only those elements, which are essential to a full and clear disclosure of the invention, are illustrated.

The machine herein illustrated, as an embodiment of our invention, includes the usual table 10, on which the work is mount-

ed and which is reciprocally mounted in ways 11, provided on the frame 12 of the machine. The table is capable of being moved in both directions, along its ways 11, by the usual means, such for example as the screw or feed shaft 13, which extends longitudinally of the ways and is capable of being driven by means of two independent power shafts 14 and 15. The shaft 14 is included in a power transmission mechanism 65 for the table, which is ordinarily termed the "cutting drive," while the shaft 15 forms a part of a power transmission mechanism, which is sometimes termed the "traverse drive" and is employed during the preliminary operation of moving the work, on the table, up to the tool, on the tool support, and also in the final operation of withdrawing the work from the tool. As illustrated, power is transmitted to the feed shaft from 75 each power shaft 14 and 15, by means of separate sets of gears, each of which is so mounted on a separate reversing plate, that it is capable of driving the shaft in either direction. Means are also employed for preventing both power shafts from being operatively connected to the feed shaft at the same time. With this arrangement the table 10 can be rapidly moved in either direction along its ways by means of the traverse drive, 80 and can also be moved in either direction by the cutting drive; but it is impossible to render the traverse drive operative, while the cutting drive is in operation, and vice versa, to render the cutting drive operative 85 while the traverse drive is in operation.

The traverse drive mechanism illustrated, includes the shaft 15, a worm 16, mounted on the shaft, a worm wheel 17, which meshes with the worm 16, a gear 18, rigidly mounted on an extending hub of the worm wheel 17, a gear 19, which is continuously in mesh with the gear 18, a gear 20, which is continuously in mesh with the gear 19, and a gear 21, which is mounted on the feed shaft 100 13 and with which either of the gears 19 and 20 are capable of being moved into mesh.

The gear 21 is shown integrally formed with a sleeve 39, which surrounds and is splined on the shaft 13. During the operation of shifting the table 10, the shaft 13 moves along the ways 11 with the table, and consequently, moves longitudinally through the sleeve 39. The sleeve is prevented from 105 110

moving longitudinally with relation to the frame 12, by means of a suitable bearing provided for it on the frame, and its co-operation with the gear 21 and a collar rigidly secured to the end of the sleeve by means of a cotter pin. The construction of the sleeve, and its co-operation with the shaft 13, can be widely varied.

The cutting drive mechanism illustrated, 10 includes the shaft 14, a worm 22, mounted on the shaft, a worm wheel 23, meshing with the worm 22, a gear 24, rigidly secured to the wheel 23, a gear 25 continuously in mesh with the gear 24, a gear 26, continuously in 15 mesh with the gear 25, and a gear 27 which is loosely mounted on the shaft 13 and with which either of the gears 25 or 26 is capable of being moved into mesh. The gear 27, as illustrated, is formed on a sleeve 28, which 20 is loosely mounted on the shaft 13 and is capable of being operatively secured to the shaft by means of a clutch device 29.

The shaft 15 is journaled in bearings 25 which are rigidly mounted on the frame 12 of the machine and the worm 16 is inclosed within a casing 31, which is rigidly mounted on the frame, and into which the shaft 15 projects and on which it is also journaled. The gears 19 and 20 are journaled on pins, 30 carried by a plate 32, which is pivotally mounted on a shaft 33, extending across and supported by the casing. The plate is provided with an integrally formed sleeve 34, which extends along the shaft 33 and on 35 which the worm wheel 17 is mounted. The worm wheel is held in place on the sleeve by means of a mutilated gear 35, which is rigidly mounted on the end of the sleeve 34, and is consequently rigidly secured to the 40 plate 32. The gears 19 and 20 are so located on the plate 32, and the shaft 33 is so located relatively to the plate, that the gear 19 is moved into mesh with the gear 21, when the plate 32 is turned to one position about 45 the shaft 33, and the gear 20 is moved into mesh with the gear 21 and consequently rotates the shaft 13 in the opposite direction from that in which it is driven by the gear 19, when the plate is turned to another position. As illustrated, the mutilated gear 50 35 meshes with a sector-shaped gear 36, which is suitably mounted within the casing 31 and is capable of being actuated, by means of a handle 37, for the purpose of 55 turning the gear 35, and of thereby turning the plate 32 to different positions, about the shaft 33. The plate 32 also co-operates with a ring 38, in controlling the operation of the clutch device 29, which is employed for 60 the purpose of operatively connecting the gear 27 to the shaft 13. As illustrated, the clutch device consists of co-operating teeth, formed on the gear end of the sleeve 28, and on the adjacent end of the sleeve 39, 65 with which the gear 21 is integrally formed.

The sleeve 28, and consequently the gear 27 are operatively locked to the shaft 13 by shifting the sleeve 28 along the shaft, so that its clutch teeth interlock with or engage the clutch teeth formed on the sleeve 39, and, vice versa, the sleeve 28, and consequently the gear 27, are operatively disconnected from the shaft 13 by shifting the sleeve so that its clutch teeth are freed or disengaged from the teeth of the sleeve 39. 70 For accomplishing this we provide gear teeth 41 on the upper or curved edge of the plate 32 and we also provide teeth 42, on the ring 38, which are continuously in mesh with the teeth 41. The ring 38 is provided on one lateral face with radially extending V-shaped grooves 38' and a ring 43, surrounding the shaft 13, is provided on its adjacent lateral face with radially extending V-shaped lugs 43' which are adapted to 75 project into the grooves 38' when the ring 38 is turned to such a position that its grooves are located immediately opposite to, or in line with, the lugs 43'. As illustrated, the ring 43 is located immediately adjacent 80 to the ring 38 and between it and the sleeve 28, and abuts against the gear end of the sleeve 28. A pin 28', carried by the frame 12, and engaging a notch 28'', formed in the ring 43, prevents the ring 43 from turning, 85 relatively to the frame, but permits it to move longitudinally, with relation to the shaft 13, when the ring 38 is turned.

The plate 32 and the ring 38 are so located, relatively to each other, that the ring 100 will occupy a position such that its grooves 38' are in alignment with the lugs 43' when the plate 32 occupies the intermediate position, that is, the position in which neither of the gears 19 and 20 are in mesh with the 105 gear 21. When the plate is in this position the sleeve 28 may be moved longitudinally along the shaft 13, for the purpose of operatively connecting the gear 27 to the shaft: and when so moved, the lugs 43' move into 110 the grooves 38'. When the plate 32 is turned so as to move either of the gears 19 or 20 into engagement with the gear 21, the ring 38 is turned, relatively to the ring 43, and consequently the lugs 43 are caused to 115 ride out of the grooves 38'. This causes the ring 43 to move laterally away from the ring 38, and to thereby move the sleeve 28 along the shaft to such a position that the clutch device 29 is disengaged and the gear 27 is operatively disconnected from the shaft 120 13. In addition to this the co-operation between the rings 38 and 43 prevents the sleeve 28 from being shifted, so as to render the clutch device effective, when the plate 125 32 is turned so as to render either of the gears 19 or 20 operative as driving agents, of the shaft 13. In Fig. 3 the rings 38 and 43 are shown in the relative positions they occupy when one or the other of the 130

gears 19 or 20 is in mesh with the gear 21; and, it is apparent, that the lugs 43, abut-
5 tir against the lateral face of the ring 38, pi-
ent the sleeve from being moved to
5 render the clutch mechanism operative.

In the drawings we have provided means
for automatically moving the plate 32 to
the intermediate position, in which neither
of the gears 19 or 20 are in mesh with the
10 gear 21, and in which the ring 38 occupies
such a position, relatively to the ring 43,
that the sleeve 28 may be moved to opera-
tively connect the gear 27 to the shaft 13.
As illustrated, the plate 32 is provided with
15 a downwardly extending projection on
which a laterally extending pin 32' is
mounted. The pin 32' projects into a tube
48 which extends across the casing 31 at
right angles to the shaft 33, and the pin is
20 engaged by spring-actuated plungers 49 and
51, which are located within the tube, and
on opposite sides of the pin. The tube is
also provided with a partition 52, semi-cir-
25 cular in cross-section, which is located mid-
way between its ends and against which the
plungers 49 and 51 are held when in their
normal positions. When the plate is tilted
in one direction so as to move the gear 19
30 into mesh with the gear 21, the plunger 49
is moved from its normal position by the
pin 32', and the tension of its controlling
spring tends to move it and the pin back
to a central position with relation to the
35 tube. As soon as the actuating handle 37
is released, the plunger is moved by its
spring, to the normal position, and conse-
quently moves the plate 32 to the interme-
diate position. When the plate is moved in
40 the opposite direction, by the handle 37, the
plunger 51 is moved from the normal posi-
tion, and it, like the plunger 49, returns the
plate to the intermediate position, as soon
45 as the actuating handle 37 is released. The
partition 52 is provided in the tube 48 and
is located in a central position between the
plungers, so that the returning force of one
plunger will not be minimized by an op-
50 posing pressure from the other plunger.
With this arrangement the plate 32 nor-
mally occupies the central position and the
traverse drive is normally inoperative.

The gears 25 and 26 of the cutting drive
are journaled on pins which are carried by
a plate 44, and the plate is pivotally mount-
55 ed on the shaft 33, it being understood that
the casing 31 incloses the worm 22, as well
as the worm 16, and that the shaft 14 pro-
jects into and is journaled on the casing.
The plate 44, like the plate 32, is provided
60 with an integrally formed sleeve, which
projects longitudinally along the shaft 33
and upon which the gear wheel 23 is jour-
naled. The plate 44 is provided with a
handle 45, and is capable of being locked
65 in different positions by means of a spring-

projected finger 46, which engages a notched
sector 47 and is capable of being withdrawn
from the notches of the sector by a move-
ment of the handle 45. As illustrated, the
sector is provided with three notches, so 70
located that the plate 44 can be locked in
three positions; one in which the gear 25
is in mesh with the gear 27; an intermediate
position, in which neither the gear 25 or 26
are in mesh with the gear 27; and a third 75
position, in which the gear 26 meshes with
the gear 27. With this arrangement the
plate 44 may be locked in such a position
that either the gear 25 or the gear 26 may
be employed in driving the gear 27, and con- 80
sequently the gear 27 and the shaft 13 may
be driven in one direction or the other, by
the power shaft 14 of the cutting drive
mechanism.

In the drawings we have illustrated man- 85
ually operable means for shifting the sleeve
28 along the shaft 13 and thereby opera-
tively connecting or disconnecting the gear
27 from the shaft 13. The means illus- 90
trated comprises a yoke 55 which engages an
annular slot 56, provided in the sleeve 28,
and which is rigidly secured to a rotatable
bar 57. The bar 57 projects beyond the
frame 12 at a convenient position, and is 95
provided, at its outer end, with an actuating
handle 53, which may be moved in either di-
rection for the purpose of shifting the sleeve
28, so as to render the clutch device 29 op-
erative, or inoperative. A spring-pressed 100
detent 54 is provided for the purpose of
yieldingly holding the yoke, and conse-
quently the sleeve, in the positions to which
it is moved by the handle 53. As illustrated,
the detent is mounted within a suitable aper- 105
ture formed in the frame 12 and engages
slots or openings provided in the bar 57.
We have also provided means for automatic-
ally actuating the yoke to disconnect the
clutch mechanism when the table has 110
reached a predetermined position along its
ways. As illustrated, the bar 57 is pro-
vided with an integrally formed gear 60 and
a co-operating rack 61, which projects down-
wardly through a suitable way formed in 115
the frame 12. The upper end of the rack
is beveled and is capable of being engaged
by a bolt 62, which is adjustably mount-
ed on the table and may be moved to differ-
ent positions along it. When the bolt 62 120
is moved, by the table, into engagement with
the head of the rack 61, it depresses or shifts
the position of the rack and consequently
turns the bar 57 and the yoke 56. This
shifts the sleeve 28 away from the sleeve 125
39 and renders the clutch device 29 inopera-
tive; or in other words, the shifting of
the rack operatively disconnects the gear 27
and permits it to rotate independently of
the shaft 13.

When it is desired to employ the traverse 130

drive mechanism in shifting the table 10, the lever 37 is shifted to one extreme position or the other. This shifts the plate 32 to one extreme position or the other and moves either the gear 19 or the gear 20 into mesh with the gear 21, and incidentally turns the ring 38 so that it shifts the ring 43, through the agency of the coöperating ribs 43' and grooves 38', and thereby renders the clutch device 29 inoperative. Power is then transmitted to the table from the shaft 15, through the gears 16, 17 and 18, one or the other of the gears 19 or 20, the gear 21, the sleeve 39, the shaft 13, and the means employed for operatively connecting the shaft to the table. During the operation of the table, the shaft 13 moves longitudinally of the sleeve 39, as is customary in such mechanisms. While the traverse drive is operative, in shifting the table 10, the feed or cutting drive cannot be rendered operative, since the coöperation between the rings 38 and 43 prevents the clutch device 29 from being rendered operative or, in other words, prevents the sleeve 28, and its gear 27, from being operatively connected to the shaft 13. When the lever 37 is moved to the intermediate position, the plate 32 is also moved to the intermediate position and both of the gears 19 and 20 are free of the gear 21, and consequently, the operative connection between the traverse drive and the shaft 13 is broken. The moving of the lever 37 and the plate 32 to their intermediate positions, also turns the ring 38, so that the clutch device 29 is capable of being rendered operative. In the apparatus illustrated, the lever 53 is provided for the purpose of shifting the sleeve 28 longitudinally with relation to the shaft 13 and of thereby rendering the clutch device operative, or, in other words, positively connecting the sleeve 28 to the sleeve 39, which, as has been described, is splined to the shaft 13. After the traverse drive has been rendered inoperative in the manner above described, the plate 44 may be shifted from the intermediate position, through the agency of the lever or handle 45, and may be locked into either of its extreme positions. This moves one or the other of the gears 25 or 26 into mesh with the gear 27, and consequently, drives the sleeve 28 in one direction or the other. After this has been accomplished, the clutch device may be rendered operative by turning the lever 53. When it is desired to render the cutting drive mechanism inoperative and the traverse drive operative, all that is necessary is to shift the lever 37, and, as has been described, this will render one or the other of the gears 19 or 20 effective as driving agents of the gear 21, and will also render the clutch device 29 inoperative.

65 In accordance with the United States

Patent Statutes, we have illustrated and described the preferred embodiment of our invention, but we desire it to be understood that various changes, modifications and substitutions may be made in the apparatus 70 illustrated, without departing from the spirit and scope of our invention as set forth in the appended claims.

What we claim is:

1. In a machine of the character described, 75 a reciprocable table, a driving agent for the table, two separate power shafts for driving said agent, a separate gear train between each power shaft and said agent, means for shifting one of said gear trains to render its 80 coöperating shaft effective in driving said agent in both directions and for operatively disconnecting the shaft from the agent, and means controlled by the first-mentioned means for operatively disconnecting the 85 other gear train from said agent.
2. In a machine of the character described, a rotatable driven agent, two separate power shafts for driving said agent, a power transmission mechanism between one shaft and 90 said agent, a gear train driven by the other shaft and capable of being shifted into and out of operative connection with said agent, and means controlled by the shifting of said gear train for rendering said power 95 transmission mechanism inoperative as the driving agent of said driven agent.
3. In a machine of the character described, a reciprocable table, a feed shaft for actuating the table, a cutting drive mechanism for 100 actuating the feed shaft, a traverse drive mechanism for actuating the feed shaft, comprising a power shaft, a gear train, a reversing plate for shifting the gear train into and out of operative connection with the feed shaft, and on which a gear of said train is mounted, and means actuated by the reversing plate for operatively disconnecting the cutting drive from the feed shaft, when the plate is shifted to operatively connect 105 the gear train to the feed shaft.
4. In a machine of the character described, a reciprocable table, a driving agent for the table, a cutting drive mechanism for actuating the driving agent, a traverse drive mechanism for independently actuating the agent and including a gear train, a reversing plate for shifting the gear train into and out of operative connection with the driving agent, and for reversing the driving agent, and 115 means, comprising a clutch device, actuated by the reversing plate for operatively disconnecting the cutting drive mechanism from the agent when the plate is shifted to 120 operatively connect said gear train to the agent.
5. In a machine of the character described, a reciprocable table, actuating means for the table, two separate power shafts for driving 125 said means, a separate gear train between

- each shaft and said means, each gear train including an ahead gear and a reversing gear, and a reversing plate, on which said gears are mounted, for shifting one or the other of the gears into or out of operative connection with said means, a clutch device between one of said gear trains and said means, and means actuated by the reversing plate of the other gear train for disengaging the clutch device and for thereby operatively disconnecting its corresponding gear train from said first mentioned means.
6. In a machine of the character described, a reciprocable table, a shaft for actuating the table, a gear operatively connected to the shaft, a gear train for coöperating with said gear to drive the shaft, a reversing plate for moving one or another of the gears of the train into mesh with said first mentioned gear, a second gear loosely mounted on the shaft, a second gear train for actuating said second gear, a clutch device for operatively connecting the second gear to the shaft, and means actuated by the reversing plate of the first mentioned gear train for disengaging the clutch device to operatively disconnect said second gear train from said shaft.
7. In a machine of the character described, a reciprocable table, an agent for actuating said table, two independent power transmission mechanisms for actuating said agent, a clutch mechanism for operatively connecting one power transmission mechanism to, and for operatively disconnecting it from, said agent, means for controlling the operation of the second power transmission mechanism and for disengaging said clutch device when the second power transmission mechanism is operatively connected to said agent, and means, actuated by the table, for disengaging said clutch device.
8. In a machine of the character described, a reciprocable table, a rotatable shaft for actuating the table, a power transmission mechanism for actuating the shaft, a clutch device for operatively connecting said power transmission mechanism to, and for disengaging it from, said shaft, a second power transmission mechanism comprising a gear train, a plate for shifting said gear train into and out of operative connection with said shaft, means actuated by said shaft for disengaging said clutch mechanism when said gear train is shifted into operative connection with said shaft and means for automatically shifting said plate, so as to operatively disconnect said gear train from said shaft.
9. In a machine of the character described, a reciprocable table, a driven shaft for actuating said table, two power shafts for actuating said driven shaft, a separate gear train between each power shaft and said driven shaft, a clutch device included in one of said gear trains, a reversing plate for moving the other gear train into and out of operative connection with the driven shaft, means actuated by the plate for disengaging the clutch device and automatic means for moving the plate and said means to the normal position, in which the gear train controlled by the plate is operatively disconnected from the driven shaft.
10. In a machine of the character described, a reciprocable table, a driven shaft for actuating the table, a connecting feed drive for actuating the shaft, comprising, a power shaft, a gear train including a forward and a reversing gear, and a reversing plate on which said forward and reversing gears are mounted, a clutch device between said gear train and said driven shaft, for rendering said gear train operative or inoperative as a driving agent for the driven shaft, a traverse drive mechanism comprising a power shaft, a gear train, including a forward and a reversing gear and a reversing plate, on which said forward and reversing gears are mounted, for moving one or the other of the gears into operative engagement with the power shaft, means actuated by the reversing plate of the traverse drive mechanism for disengaging the clutch device, and means for automatically moving said last-mentioned reversing plate to an intermediate position and thereby operatively disconnecting the gears mounted thereon from said driven shaft.
11. In a machine of the character described, a reciprocable table, a driven shaft for actuating the table, a transmission mechanism for actuating the shaft, a clutch device for rendering said mechanism operative or inoperative as a driving agent of the shaft, a plate for controlling said mechanism, to reverse the rotation of the shaft, means for locking said plate in different positions, a gear train for actuating the shaft, a reversing plate included in the gear train, for shifting the gear train to reverse the rotation of the shaft, and to operatively disconnect the gear train from the shaft, means actuated by the reversing plate for disengaging the clutch device, manually operable means for controlling the operation of the clutch device and automatic means tending to move the reversing plate into an intermediate position and thereby operatively disconnecting the gear train from the shaft.
12. In an apparatus of the character described, a reciprocable table, a driven shaft for actuating the table, two independent power transmission mechanisms for actuating the driven shaft, a clutch device for operatively connecting and disconnecting one power transmission mechanism and the shaft, means for operatively connecting and disconnecting the other power transmission mechanism and the shaft and for disengaging the clutch device, and automatic means,

controlled by the movement of the table, for disengaging the clutch device.

13. In a machine of the character described, a reciprocable table, a driven agent 5 for actuating the table, two separate power shafts for driving said agent, a clutch device between one power shaft and said agent, means for disengaging the clutch device and for rendering the other power shaft effective 10 as a driving agent for the driven agent, and means controlled by the table for disengaging the clutch device.

14. In a machine of the character described, a reciprocable table, a worm for 15 actuating the table, two separate power shafts for driving said worm, a separate gear train

between each power shaft and the worm, means for rendering one of said gear trains effective or ineffective as a driving agent for the worm, a clutch device controlled by 20 said means, for rendering the other gear train ineffective as a driving agent for the worm, and means, actuated by the table, for disengaging said clutch device.

In testimony whereof, we have hereunto 25 subscribed our names this 22nd day of January, 1913.

RICHD. K. LE BLOND.
